HOLDER FOR CONDIMENT DISPENSERS

Robert W. Greco, Brooklyn, N. Y.

Application September 4, 1956, Serial No. 42,822

Term of patent 3½ years

(Cl. D44—24)

Fig. 1 is a front elevational view of a holder for condiment dispensers, showing my new design;

Fig. 2 is an end elevational view of the same; and

Fig. 3 is a top plan view of the same.

I claim:

The ornamental design for a holder for condiment dispensers, as shown.
